D. S. HOWARD.
DREDGING MACHINE.

No. 104,594.

Patented June 21, 1870.

United States Patent Office.

D. S. HOWARD, OF LYONS' FALLS, NEW YORK.

Letters Patent No. 104,594, dated June 21, 1870; antedated June 11, 1870.

IMPROVEMENT IN DREDGING-MACHINES.

The Schedule referred to in these Letters Patent and making part of the same

To all whom it may concern:

Be it known that I, D. S. HOWARD, of Lyons' Falls, county of Lewis, State of New York, have invented certain Improvements in Dredging Machinery; and I do hereby declare the following to be a full, clear, and exact description of the same.

My invention consists in certain improvements in dredging machinery, fully described hereafter, by which I am enabled to adapt one machine to all varieties of work, instead of having to employ a separate machine, as heretofore, for each change in the condition of the work, or in the nature of the material to be excavated.

The improvements are also such that fewer attendants and less steam-power for a given amount of work are required than with other dredging-machines.

In order to enable others familiar with machinery of this class to make and use my invention, I will now proceed to describe its construction and operation, reference being had to the accompanying drawing, which forms a part of this specification, and in which

Figure 1 is a sectional elevation of my improved dredging-machine;

Figure 2, a front elevation of the same;

Figure 3, a plan view; and

Figures 4, 5, and 6, detached views drawn to an enlarged scale, and illustrating portions of my invention.

Similar letters refer to similar parts throughout the several views.

Before proceeding to describe my invention, it will be well to state that no dredging-machine as heretofore constructed has been found equally well adapted to all kinds of works.

Some excavations, for instance, commenced in the water, require to be continued through dry land, and the excavated material to be conducted over the sides of the machine, and deposited upon the banks. At other places the height of the banks requires the excavated material to be put into lighters, and, as the latter cannot, in all cases, be placed alongside the machine, the deposits must be made over the stern.

Other work is situated in water of sufficient depth to float the machine and lighters, in which case another modification of machinery, economically adapted to the situation, will be required.

There are variations of the material also which require machines of very different construction in their excavation.

My machine, which I will now proceed to describe, is designed to perform all kinds of dredging, and to thus overcome the objections arising from the employment of a different machine for each variety of work.

On reference to the drawing—

A represents the hull of the machine, upon which is mounted the frame B.

C is the driving-shaft, to which motion is communicated from the engine (not shown in the drawing) by any suitable system of gearing, and upon this shaft are pinions *a*, gearing into cog-wheels *a'*, of a shaft, D, which extends entirely across, and turns in suitable bearings in the frame-work B.

To the shaft D are hung the toothed chain-wheels *b b b b*, by which the two sets of chains E E and E' E' are turned in a manner common to ordinary dredging-machines.

These chains, as well as the buckets F, which are attached to the same, form important features of my invention, and will be more fully described hereafter.

The lower ends of the chains pass around and are arranged to drive toothed wheels *b*, similar to the wheels *b*, which are hung to a horizontal shaft, G, the latter being supported near each end by two bars H and H', each of which has on one side a rack, *c*, gearing into a pinion, *c'*, and the pinions of the bars H' are connected by cog-gearing, shown in fig. 1, with a crank spindle, *d*, by means of which the said bars and shaft G may be raised or lowered, as required.

On the shaft G, between the two sets of buckets, is a cylinder, I, which may be made hollow and air-tight, and upon which a number of spiral blades or scrapers, *e*, are so arranged that they shall convey the material to be excavated from the center toward each set of buckets; and upon the same cylinder are a number of hooks, *f*, which dig into and loosen the material when the cylinder is turned, (see fig. 2.)

As the hooks *f* may not be equally well adapted for all kinds of work, other appliances can, when necessary, be attached to the cylinder or blades.

In addition to the cylinder I, there are also, at the opposite ends of the shaft G, two shorter cylinders I', likewise furnished with hooks *f*, or their equivalents, and with spiral blades *e*, for conveying the material toward the buckets.

After passing over the upper wheels *b*, the chains E and E' do not descend directly to the lower wheels *b'*, but each set is conveyed nearly horizontally for a short distance, and caused to pass around flanged wheels *g*, which are hung to a shaft, *g'*, arranged to turn in a movable frame, K.

One of these frames is shown in fig. 1, and consists of two side pieces, suitably connected together, and supported at one end by rollers, which run upon ascending ways *h*, and at the opposite end by toothed pinions *i*, adapted to racks *i'*, which are secured to descending ways *h'*.

The pinions *i* are hung to a spindle which can either be turned by hand, by means of cranks, or be connected by any suitable gearing to the driving-shaft, the carriages being moved by these pinions in such a manner as to permit the raising or lowering of the

chains of buckets and of the cylinders I and I', and so as to tighten the chains after such adjustment.

A movable spout, L, which is arranged to slide freely in a stationary spout, M, by which the excavated material is deposited over the stern of the dredge, is so attached to the axis of the flanged wheels g, at a point adjacent to each set of buckets, that it shall move with and always maintain the same position in respect to the said flanged wheels.

N, figs. 1 and 3, is a four-sided floating tank, attached to an extension, B', of the frame B at a point about twenty-five feet to the rear of the machine, and arranged to be turned to any desired position by means of pinions gearing into a circular rack, and operated by a lever, k.

One object of this tank is to counterbalance the weight of the machinery, necessarily placed ahead of the hull, in order to enable the dredge to clear its own way, another object being to serve as a means of moving the lighters in which the excavated material is deposited. For instance, an empty lighter can be attached to the outer side of the tank, and a loaded one to the opposite side, the tank being then turned half way round so as to change the positions of the two lighters, the empty one being brought to a position beneath the spouts M ready to be filled, while the loaded one is turned to a position most convenient for its removal.

The counterbalance may also be used as a tank for the engine, to be filled on commencing work before the water has been disturbed by the dredging.

My improved dredger is operated in a manner similar to that of other machines of its class, it being moved forward as the work is proceeded with by means of tackle attached to a pulley or pulleys anchored at a convenient distance ahead.

Motion in the direction of the arrows is communicated by the gearing described to the spiral cylinders I and I', and to the buckets, which together clear the way to the full width of the dredge, and to the depth required, the material as it is excavated being carried up by the buckets over the wheels b and g, and dumped into the spouts L, to be conveyed by the latter to the spouts M, and thence to the lighters, as before described.

The bucket F, shown in the enlarged views, figs. 4 and 5, is furnished with a loose bottom, p, which, when the bucket is inverted, opens sufficiently to permit the admission of air into the interior of the bucket, and this insures the discharge of the load, however tenacious the material may be.

This bucket, however, is intended to be used only when the machine is arranged as above described, that is, for depositing the excavated material at the stern, a bucket of different construction being required when the deposit is to be made over the sides through the spouts x x, fig. 2, or at any other point.

In order to enable the buckets to be charged with facility, and without involving the necessity of separating the links of the chains, I construct the latter in the manner shown in fig. 6, each chain being made up of long and short links s and s', with intervening washers s'', and the whole being connected together by suitable rivets or bolts.

The buckets are furnished with lugs t, which are introduced into the spaces between the short links s', and fastened by a rod passing through holes in the said links and lugs.

This arrangement of links also enables a gang of hooks, or other device best calculated to loosen the material to be excavated, to be attached to the chain between the buckets.

It will be observed, on reference to fig. 1, that the working portion of the chains is always maintained in a perpendicular position, this enabling the usual pulleys, ways, &c., necessary when the chains are worked

at an angle, to be dispensed with, and greatly reducing the friction, especially where no lubricating material can be used, nor the wearing parts secured from the destructive action of sand and water which must always be present in dredging.

The flanged wheels g, also, by maintaining a portion of the chains in a nearly horizontal position, enable the buckets to be dumped with facility when a lateral deposit is to be made.

In some cases, when there is sufficient depth of water, a lighter can be placed in front of the machine, and buckets of peculiar construction be arranged to dump into a short spout directly from the perpendicular portion of the chains.

It will be well to mention here that the digging and conveying cylinders I and I', if made hollow, can be furnished with stop-cocks, through which water can be passed into the interior of the said cylinders or discharged from the same, according to their required weight, and the nature of the material to be excavated.

By the arrangement of the cylinder-shaft on the projecting end of the bar H', instead of at the lower end of the bar H, as heretofore, I am enabled to bring the chain of buckets to a vertical position, as shown in fig. 1, without the necessity of placing the machinery so near the end of the boat as would otherwise be required.

I do not claim, broadly, a shaft provided with a spiral blade which feeds the earth to a chain of buckets, as spiral blades have heretofore been arranged on and secured to arms upon a revolving shaft, but are inefficient, as branches, stones, &c., catching beneath the blades, and between the arms, wrench the same from the shaft.

The spaces between the arms also become clogged with earth, &c., so as to prevent the blades from carrying the soil laterally, as desired.

When the blades are arranged upon a drum, as above described, they form channels which cannot become clogged, while it is impossible for stones or branches to become entangled with the blades so as to detach the same.

It will be evident, without further description, that machinery constructed, arranged, and operating as above described, will be adapted to a great variety of work, and will be much more economical than machines of a special character, as heretofore constructed.

I claim as my invention and desire to secure by Letters Patent—

1. The within described arrangement of the bars H, H', and cylinder-shaft G, the latter revolving in bearings at the end of the shaft H', and the two shafts being jointed together, as specified.

2. The hollow cylinder I, with its spiral blade or blades arranged on its face, substantially as described.

3. The hollow drums or cylinders I, operating as described, and provided with cocks, for the purpose set forth.

4. The chains E and E', when composed of long and short links s and s', and intervening washers s''.

5. The buckets F, with their loose bottoms or valves p, arranged to open slightly when a load is to be discharged, as herein described.

6. The adjustable tank or counterbalance N, attached to an extension of the frame at the rear of the dredge, substantially as herein set forth.

7. The carriage K, with its spout L, in combination with the chute M, as described.

In testimony whereof I have signed my name to this specification in the presence of two subscribing witnesses.

D. S. HOWARD.
